UNITED STATES PATENT OFFICE.

EDWIN E. SLICK, OF WESTMONT BOROUGH, PENNSYLVANIA.

FRICITION-SPRING DRAFT-RIGGING.

1,171,809.

Specification of Letters Patent.

Patented Feb. 15, 1916.

Application filed October 30, 1913. Serial No. 798,178.

To all whom it may concern:

Be it known that I, EDWIN E. SLICK, a citizen of the United States, residing in the borough of Westmont, in the county of Cambria and State of Pennsylvania, have invented certain new and useful Improvements in Friction-Spring Draft-Rigging; and I do hereby declare the following to be a full, clear, and exact description of the invention, such as will enable others skilled in the art to which it appertains to make and use the same.

My invention relates to draft rigging for railway cars, with special reference to the form of friction spring draft rigging described herein.

My invention is applicable to the usual arrangements of draft sills, coupler, and coupler yokes, but the spring portion of my rigging, which is adapted to withstand the pulling and buffing stresses and to cushion the same, thus preventing shock on the car structures, is a particular part of my invention.

The springs of my draft rigging are formed of comparatively thin plates of steel which may be square or rectangular or of other outline, and these plates are provided with corrugations or waves, the axes of which are preferably parallel to each other, so that each corrugation acts as a spring when compressed. I use a number of these corrugated spring plates, the corrugations of which are disposed angularly with respect to the corrugations of the adjoining plates, in such a way that the projecting portions of the contacting plates are adapted to press against each other so that each plate forms an abutment against which its adjoining plate operates. I may make my corrugated spring plates singly, or if it is desired to have greater spring action, I may make them laminated, that is composed of two or more corrugated plates nested within each other, the corrugations of each compound plate being substantially parallel. By reason of this construction, my corrugated spring plates act in withstanding stresses, first by the elasticity and spring action of the corrugated portions, which when subjected to pressure tend to flatten out or become straight, and in addition to this the movement of one corrugated spring on the adjoining spring is attended with a considerable amount of frictional resistance, so that my group of corrugated springs acts

both by the elasticity of the spring plates in bending, and by the friction of the contacting parts of the same when moving on each other. In addition to this it should be noted that the bending or flexure of each corrugated portion of my spring has the tendency to produce an arch action, in that a thrust or compressive force is carried through the curved portion of each corrugation in such a way as to counteract to a certain extent the tensile forces of that side of the spring plate which is subject to tensile stresses. This arch action therefore tends to lessen the tensile stresses which are due to bending and makes each plate more serviceable and capable of withstanding the stresses and performing its functions as described.

I prefer to make my plates of hard or spring steel which are rolled or pressed to form, either before or after being cut to lengths, and these plates are preferably hardened by heating them to the proper temperature dependent upon their composition, then quenching in oil or other cooling medium and afterward the temper is drawn to the required degree by heating them to a temperature less than that before quenching. I may also give my spring plates special treatment by double heating, double quenching, and drawing the temper, which with some kinds of steel will produce a more amorphous structure and one that is very well adapted to serve the purposes intended. I also may make the depths of the corrugations in my spring plates such that when each plate is flattened or nearly flattened by the pressure to which it is subjected, the stresses in the same will just about equal the proper working stress for this class of material, and this mode of construction will insure that the plates remain intact and capable of the best and longest service.

Having thus given a general description of my invention, I will now, in order to make the matter more clear, refer to the accompanying two sheets of drawings which form part of this specification and in which like characters refer to like parts:

Figure 1 is a top plan view of my improved draft rigging and enough of the car to show the manner of mounting the same. Fig. 2 is a vertical longitudinal sectional elevation taken on the line II—II of Fig. 1. Fig. 3 is a vertical transverse sectional elevation taken on the line III—III of Fig. 1. Fig. 4 is a front elevation of one of the

cheek plates with the guide plate attached thereto, the draft lugs being shown as formed integral with the cheek plate, and enough of the draft sills are shown to illustrate the manner of attaching the cheek plate thereto. Fig. 5 is a top plan of my corrugated buffer and draft springs arranged for use in one form of my apparatus. Fig. 6 is a top plan view of my corrugated buffer and draft springs assembled in a slightly different manner from that illustrated in Fig. 5. Fig. 7 is a view similar to Fig. 5 but showing the springs with fewer corrugations of greater radii of curvature. Fig. 8 is a top plan view of my corrugated springs similar to Fig. 7 but with each spring formed two-ply or laminated. Fig. 9 illustrates a plurality of my corrugated and laminated springs similar to Fig. 8 but formed three-ply. Fig. 10 is a top plan view of another manner of forming and arranging my springs with about one corrugation each. Fig. 11 is a transverse section of a portion of one of my corrugated springs showing the manner of forming it of varying thickness, proportional to the stresses and deflections to which it will be subjected in use.

Referring now to the characters of reference on the drawings:—The draft sills of a car are indicated as 1, the end sill of the same as 2, and the top cover plate of the end sill is indicated as 3. The buffer block of the car is indicated as 4, the carry iron, which supports the coupler by the shank thereof, is indicated as 5, the coupler head is indicated as 6, the shank of the coupler is indicated as 7, and the shoulders on the inner end of the coupler shank are indicated as 8. The coupler yoke is indicated as 9, the rivets connecting the ends of said yoke to the inner end of the coupler shank are indicated as 10, while the inwardly bent ends 11 of the coupler yoke further aid in securing said yoke to the shank. The front follower block of the draft rigging is indicated as 12, the rear follower block is 13, while 14 is a wear plate secured to the inner end of the yoke as shown. The corrugated springs which adjoining the follower blocks are indicated as 15, the adjacent ones are indicated as 16, and those in the central portion of the group of springs are indicated as 17. I may make all these springs of the same thickness or I may make the end springs the thickest, the springs adjoining the end slightly thinner, and the central springs still thinner, in which case the thinner springs will first take up the pull or push with less resistance, and as the pull or push continues, this will then be taken up by the next set of slightly thicker springs and finally the thickest will come into action, thus providing a cumulative effect.

It will be noted that the corrugations of the springs are arranged alternately in different directions, so that the projecting portions of the corrugations where these touch each other are adapted to ride on each other on approximately straight lines. This arrangement of springs with the axes of the corrugations of one spring disposed in one direction and that of the adjacent spring at an angle to said direction is a particular and important feature of my invention, as this provides a spring resistance and also a frictional resistance during the compression and release of said springs by the sliding of the surface of one spring on the adjacent spring, and there is also a further arching effect in each corrugation whereby the tensile stresses, which would otherwise be so great as to tend to break the spring, are counteracted by the compressive force due to the arch action, thus enabling the springs to withstand more work per unit of volume or weight than simple springs of ordinary construction.

The cheek plate of my draft rigging is indicated as 18, the top guide plate, which is shown as formed integral with the cheek plate, is 19. These top guide plates 19 serve to guide and hold the upper portions of the springs and their edges serve to guide the upper part of the yoke. It will be noted that the cheek plates have lateral guides formed integral therewith, the top lateral guide portions being indicated as 45 and the lower lateral guide portions being indicated as 46. The bottom guide plates removably secured to the cheek plates and draft sills are indicated as 20. It will thus be seen that my spring plates are enclosed between the cheek plates by an open box-like structure whereby all edges of the spring plates are held in position and the plates in proper relation with each other and the other parts of the apparatus, while at the same time they are free to move longitudinally of the draft rigging when they are forced together or expand in operation. It should also be noted that the bottom guide plates can be readily removed, so as to permit the draft rigging to be lowered and removed, and it can be replaced by a reverse operation.

The forward draft lugs or abutments which are shown as formed integral with the cheek plates are indicated as 21 and the rear draft lugs or abutments which are similarly formed integral with the cheek plates are indicated as 22.

23 are depressions or recesses formed in the intermediate portion of the cheek plates for the purpose of receiving the heads of the rivets 24 or bolts which secure this portion to the draft sills, the rivet or bolt heads thus being counter-sunk below the principal inner surface of the cheek plates in such

a way that they will not touch nor interfere with the movement of the spring plates and followers. The end portions of the cheek plates are provided with similar depressed portions 25 through which rivets 26 or bolts are passed to further secure the cheek plates to the draft sills and these portions together with other parts of the cheek plates are reinforced by the marginal flanges as clearly shown on the drawings. The bottom guide plates are removably secured to the lower portion of the cheek plates by the bolts 27 as shown.

Referring now to Fig. 5, this shows either a side or top view of an arrangement of a set or part of a set of my corrugated spring plates, the left hand one being arranged with the axes of its corrugations horizontal and the adjacent plate with the axes of its corrugations vertical, and the other plates are similarly arranged alternately. In this view the end plates 15 are shown of greater thickness than the plate 16, and the plates 17 are still thinner, for reasons previously explained herein.

Referring now to Fig. 6 this shows a slightly different combination of plates, the end one on the left hand side being arranged in a manner similar to that illustrated in Fig. 5, whereas a portion of the plates indicated as 28 are arranged with the axes of their corrugations parallel. These plates 28 will therefore offer less resistance to flexure than the other ones which are alternately arranged with their axes at angles to each other, one reason for this being that the frictional resistance will be less with the arrangement of the plates 28 than that of the others. This therefore gives a more yielding movement for the initial pressures and if further movement is needed, this will then be taken care of by the other plates 15, 16, and 17 in the same group.

Referring now to Fig. 7, the end springs which are illustrated as 29 are considerably thicker than the intermediate springs 30, which springs 30 are somewhat thicker than the thinnest ones of this group indicated as 31. By means of this arrangement, the thin springs 31 will accommodate the first pressures, the thicker springs 30 will then accommodate further pressures and finally the thickest springs 29 will come into action thereby producing a cumulative effect.

Referring now to Fig. 8 the end springs 32 are formed two-ply and each ply is of greater thickness than that of the next sets of two-ply springs 33, which latter are thicker than the next sets of springs 34. By means of this two-ply arrangement a greater amount of deflection will be provided for any given pressure than with the thicker springs formed of single plates. Referring now to Fig. 9 all these springs are formed three-ply, the end springs 35 are the thickest, the

intermediate springs 36 are of slightly less thickness, while the other groups of springs indicated as 37 are the thinnest. The action of the set of springs shown in Fig. 9 is similar to that described in Fig. 8.

As shown in Fig. 10, the springs are provided with but one full corrugation, but near the end portions of said corrugation is a portion of another corrugation adapted to form bearing surfaces on the adjacent spring. In this figure the springs 38 are indicated as of the greatest thickness, the intermediate springs 39 are of slightly less thickness, while the springs 40 are the thinnest. On account of the long curves of the springs shown in Fig. 10, these will withstand greater deflections than those of shorter corrugations.

Referring now to Fig. 11, this is the cross-section of a portion of a particular form of my corrugated spring indicated generally as 41, the central portion 44 of each corrugation being formed of comparatively thick material joined to the next corrugation by thinner portions 43 as shown, the end portion of this spring being indicated as 42. As the stresses in a spring of this character when subjected to flexure are greater at the centers or apices of the corrugations, I provide for this by making the material thicker at these points as shown, and as these stresses diminish gradually toward the points of support, I consequently diminish the thickness of the material in these directions. As, however, this action is somewhat similar for each corrugation the thinnest part of my spring is not at the end contact, or bearing portions thereof, but is intermediate between the apices of the corrugations as shown. By means of this construction, I provide a spring which is particularly well adapted to its work, is economical of material, and adapted to produce the results desired with the use of a minimum amount of material.

Although in certain cases I have shown my groups of springs in various thicknesses as heretofore explained, I may make these all of the same thickness as shown in certain portions of the illustrations herein, and although I have shown my corrugated springs in connection with a draft rigging, I wish it understood that my springs are adapted to other uses, on wheeled vehicles, as wagons, trucks of railway cars, automobiles, and otherwise.

One of the particular features of my invention resides in the construction and arrangement of groups of corrugated springs with the axes of the corrugations of adjacent springs angularly disposed, such groups being preferably retained in an inclosure adapted to guide the edges of said springs and hold them in proper relation to each other.

Although I have shown and described my invention in considerable detail, I do not wish to be limited to the exact and specific details shown and described, but may use such substitutions, modifications or equivalents thereof, as are embraced within the scope of my invention, or as pointed out in the claims.

Having thus described my invention, what I claim and desire to secure by Letters Patent is:—

1. In a railway draft rigging, a spring comprising a group of opposed corrugated plates, the direction of the corrugations in adjacent plates being angularly disposed with respect to each other, a follower plate at each end of said group of spring plates, a cheek plate on each side of said group, said cheek plates being provided with guides at their upper and lower portions, adapted to coöperate with the edges of said spring plate and thereby maintain them in operative position.

2. In a railway draft rigging, a group of opposed corrugated spring plates, the direction of the corrugations in adjacent plates being angularly disposed with respect to each other, a follower plate at each end of said group, a yoke and coupler shank surrounding said follower plates and spring plates, cheek plates provided with abutments adapted to coöperate with said follower plates, and also provided with guides at their upper and lower portions, adapted to contact with the edges of said corrugated spring plates and thereby maintain them in operative relation.

3. In a railway draft rigging, a group of opposed corrugated spring plates, the direction of the corrugations in adjacent plates being angularly disposed with respect to each other, a follower plate at each end of said group, a yoke and coupler shank surrounding said follower plates and spring plates, a cheek plate at each side of the group of spring plates, provided with abutments adapted to coöperate with said follower plates, and also provided with top, bottom and side guide portions adapted to

contact with the edges of, and thereby maintain the spring plates and follower plates in operative relation.

4. In a railway draft rigging, a spring comprising a group of corrugated plates of different thicknesses, the direction of the corrugations in adjacent plates crossing each other, a follower plate at each end of said group, a cheek plate at each side provided with abutments adapted to coöperate with said follower plates, and also provided with top, bottom and side guide portions, adapted to contact with the edges of and to maintain the spring plates in operative relation, whereby cumulative and friction spring action is provided.

5. In a railway draft rigging a group of opposed spring plates each provided with a plurality of corrugations, the direction of the corrugations in adjacent plates being angularly disposed with respect to each other, a follower plate at each end of said group, a yoke and coupler shank surrounding said follower plate and spring plates in one direction, cheek plates provided with abutments adapted to coöperate with said follower plates, and also provided with side guides and top and bottom guides adapted to contact with the edges of said spring plates and maintain them in operative position.

6. In a railway draft rigging, a spring comprising a group of plates, each plate being composed of a plurality of plates provided with a number of corrugations nested in one another, the direction of the corrugations of said combined plate crossing the direction of the corrugations of the adjacent plate, a cheek plate on each side of said group, provided with guide portions, adapted to contact with the edges of and maintain spring plates in operative relation.

In testimony whereof I hereto affix my signature in the presence of two witnesses.

EDWIN E. SLICK.
